UNITED STATES PATENT OFFICE.

WALFRED LINDGREN, OF CHICAGO, ILLINOIS.

GOLF CLUB.

Application filed August 11, 1924. Serial No. 731,422.

This invention relates to new and useful improvements in golf clubs and more particularly to clubs of this character which are of the reversible type. The main object of my invention is the provision of a golf club which combines two well-known forms of clubs and wherein the handle member attached thereto is so mounted that the same may be reversed in its position for use by either a right-hand or left-hand person without interfering with the well-known type heads attached to the handle.

Another object of my invention is the provision of a golf club the construction of which embodies two well-known forms of golf clubs, namely, mid-iron and a putter and the handle is so attached to the head that it may be quickly and readily reversed in its position to be used by either a right-hand or left-hand person.

A further object of my invention is the provision of a combined head for golf clubs having means for adjustably attaching the handle member thereto and also includes means whereby the handle may be securely retained in an adjusted position, the retaining means being of an adapted type whereby to permit ready adjustment of the handle.

With the above and other objects in view, the invention consists in the novel features of construction, the combination and arrangement of parts hereinafter more fully set forth, pointed out in the claims and shown in the accompanying drawings, in which:

Fig. 1 is a side elevation of a golf club constructed in accordance with my invention, parts thereof being broken away to illustrate the interior,

Fig. 2 is an end elevation and

Fig. 3 is a transverse section on the line 3—3 of Fig. 1.

In carrying out my invention the head comprises a substantially rectangular body 1 having a centrally disposed recess 2 and extending transversely of this recess is a bearing stud 3 upon which the head 4, as clearly illustrated in Fig. 1, is formed integral with the lower end of a socket 6 into which the handle 5 is fitted. The head 4 of the handle is provided with two flat faces 7 extending at opposite angles to each other and adapted to bear against a flat spring member 8 which is normally bored as shown in Fig. 1 with its ends mounted for sliding

movement within the slots 9 formed in the body 1 at each end of the recess 2 whereby the tension of the spring 8 will retain the head 4 against movement when either one of the flat faces 7 are moved into contact with the spring member 8.

It will be apparent that by forming the two flat faces 7 on the head 4 and extending them at opposite angles the meeting ends of the flat faces will provide a point 10 which upon turning movement of the head 4, will ride over the upper face of the spring 8 and tend to compress the same so that the ends thereof will move into the slots 9.

The head 4 is retained in position upon the stud 3 by means of a removable face plate 11 which is retained in position on the body head 1 by means of a screw 12 which extends through the plate and is embedded within the stud 3 centrally thereof. In order to prevent lateral movement of the plate 11, suitable pins 13 are carried by the body member at a point adjacent each end thereof and are adapted to be fitted into suitable openings in the plate 11. From this it will be apparent that when the screw 12 is tightened into place the plate 11 will be securely held against movement.

In the formation of my improved golf club attention is directed to the fact that the face of the body 1 opposite the plate 11 is tapered outwardly so that the outer edge of the body is considerably thicker than the inner edge; thus, forming an inclined face which is provided with a plurality of grooves 14 to form a mid-iron face. The plate 11 is also somewhat tapered transversely and the face thereof provided with angular grooves 15 to form a putter face, and from the above description it will be readily apparent that I have provided a new and improved golf club which embodies two well-known forms of club heads and wherein the handle member which is attached to the head may be quickly and readily adjusted so that the club may be used by either a right-hand or left-hand person.

Attention is directed to the fact wherein it will be noted that suitable stop shoulders 16 are formed at the outer ends of each of the inclined faces 7, said stop shoulders engaging the upper wall of the recess 2 during the rotating movement of the head 4 in order to limit the rotated movement of the head in either direction. From this it will

be apparent that when the handle 5 is moved with respect to the head 1, it will be retained in its proper balancing position with respect to the head by means of the engagement of the shoulder 16 with the upper wall of the recess 2 upon opposite sides of the opening 17 through which the socket 6 projects.

While I have shown and described the 10 preferred embodiment of my invention, it will be understood that various changes and alternations may be made without departing from the spirit of the invention or the scope of the appended claims.

Having thus described my invention, what I claim is:

1. A golf club of the class described including a recessed head portion, a movable handle head confined in the recess of the head 20 portion and having bearing surfaces extending in opposite angular directions and having portions engaging the recessed head portion limiting movement of the handle, and retaining means adapted for engagement with the bearing surfaces.

2. A golf club including a body head having one side thereof recessed and the other side provided with an inclined face, a removable plate normally closing the open 30 side of the recess and having an outer inclined face, a stud in the body extending transversely of the recess, a handle member having its inner end rotatably mounted upon said stud, flat faces on the inner end of the handle member extending in opposite direction and means carried by the head 35 and engaging said faces to retain the handle member in predetermined adjusted positions.

3. A golf club including a head having one side thereof recessed and inclined on the opposite side, a detachable plate normally closing the recess and having an inclined outer face, a movable handle having portion confined in the recess and having bearing surfaces extending in opposite angular directions and having portions engaging the head limiting movement of the handle, and retaining means adapted for engagement with the bearing surfaces. 40

4. A golf club including a head body having one side thereof recessed, a detachable plate normally closing the open side of the recess, a stud extending transversely of the recess, a handle member having head rotatably mounted upon the stud, flat faces on the head disposed at opposite angles to each other, means carried by the head body for yieldable engagement with the faces whereby to retain the handle member in predetermined adjusted positions and means for limiting the rotative movement of the handle of the head on the stud. 45

5. A golf club of the class described including a recessed head portion having opposite slots formed therein and having a bearing portion traversing the recess, a handle having portion confined in the recess and having pivotal connection to the bearing portion and having flat faces extending in opposite angular directions, and a resilient retaining member having end portions slidably engaging the slots and having portions adapted for engagement with the faces. 55

In testimony whereof I affix my signature.

WALFRED LINDGREN
